poration of Massachusetts

Application November 9, 1943, Serial No. 509,580

12 Claims. (Cl. 51—3)

The invention relates to grinding machines, and more particularly to a grinding machine for grinding both external and internal surfaces of a work piece.

One object of the invention is to provide a simple and thoroughly practical hydraulically operated grinding machine for successively grinding external and internal cylindrical surfaces on a work piece. Another object of the invention is to provide a hydraulically operated external-internal grinding machine with two independent hand operated table traversing mechanisms, one for traversing the table when in an external grinding position, and the other for operating the table when in an internal grinding position.

Another object of the invention is to provide an interlock whereby the hydraulic feed is rendered inoperative when the internal hand traverse mechanism is operative. Another object of the invention is to provide an interlock whereby the external hand traverse mechanism is rendered inoperative when the internal hand traverse mechanism is operative.

Another object of the invention is to provide an interlock which prevents initiation of a forward feeding movement of the external grinding wheel and wheel slide when the table is in an internal grinding position. Another object of the invention is to provide an interlock whereby the internal hand traverse mechanism is rendered inoperative when the work table is in an external grinding position.

A further object of the invention is to provide an electrically controlled interlock whereby the solenoid for actuating the wheel feed control valve is rendered inoperative when the work table is moved toward an internal grinding position. A further object of this invention is to provide a hydraulically operated interlock between the external hand traverse mechanism and the internal hand traverse mechanism whereby only one of said mechanisms is in an operative position.

A further object of the invention is to provide a hydraulic interlock mechanism between the external hand traverse mechanism and the internal hand traverse mechanism whereby the internal traverse mechanism is rendered inoperative when the table is in an external grinding position, and to render the external hand traverse mechanism inoperative and the internal hand traverse mechanism operative when the table is moved into an internal grinding position. Other objects will be in part obvious or in part pointed out hereinafter.

The invention accordingly consists in the fea-

tures of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of the improved external-internal cylindrical grinding machine;

Fig. 2 is a plan view of the grinding machine, as shown in Fig. 1;

Fig. 3 is an electrical wiring and hydraulic piping diagram illustrating the hydraulic actuating and the electrical controlling mechanisms of the grinding machine;

Fig. 4 is a fragmentary cross-sectional view, on an enlarged scale, taken approximately on the line 4—4 of Fig. 1, showing the external hand traverse mechanism; and

Fig. 5 is a fragmentary longitudinal sectional view, on an enlarged scale, taken approximately on the line 5—5 of Fig. 2, showing a portion of the headstock in cross section.

A combined external-internal grinding machine has been illustrated in the drawings, in which a base 10 serves as a support for a longitudinally reciprocable work supporting table 11, as shown in Fig. 4. The table 11 is arranged to slide longitudinally on a V-way 12 and flat way 13 formed on the upper surface of the base 10. The work table 11 serves as a support for a headstock 15 which rotatably supports a work piece 16 mounted on a face plate for an external and internal grinding operation (Fig. 5).

A rotatable grinding wheel 17 is supported on a wheel spindle (not shown) which is in turn journalled in suitable bearings within a transversely movable wheel slide 18. The wheel slide 18 is arranged to slide transversely relative to the base 10 on a V-way 19 and a flat way 20. An electric motor 21 is adjustably mounted on the upper surface of the wheel slide 18 and is provided with a multi-V-groove pulley 23 which is connected by multiple V-belts 24 with a multi-V-groove pulley 25 which is mounted on the right-hand end of the wheel spindle. A push button switch 22 is provided on the front of the machine base 10 to control the starting and stopping of the grinding wheel driving motor 21.

The headstock 15 is provided with a rotatable headstock spindle 26 which is journalled in suitable bearings within the headstock 15 (Fig. 5). A variable speed D. C. motor 27 is mounted on the upper surface of the headstock 15 on a platen 28

which is formed as a dovetailed slide and arranged for a transverse adjustment relative to the headstock 15 to facilitate tensioning of the driving belts. The motor 27 is provided with a multi-V-groove driving pulley 29 which is connected by multiple V-belts 30 with a multi-V-groove pulley 31 mounted on the left-hand end of the headstock spindle 26 (Figs. 1 and 2). A push button switch 32 is provided on the front of the machine base 10 to facilitate stopping and starting of the work drive motor 27. An adjustable rheostat 33 is also provided on the front of the machine base 10 which is operatively connected in the control circuit for the motor 27 to facilitate regulation of the speed of rotation of the headstock spindle 26.

A transversely movable internal grinding wheel slide 35 is mounted for a transverse adjustment relative to the base 10 on a V-way 36 and a flat way 37. The slide 35 serves as a support for a rotatable wheel spindle 38 which supports an internal grinding wheel 39. An electric motor 40 is adjustably mounted on the upper surface of the internal grinding wheel slide 35. The motor 40 is provided with a driving pulley 41 which is connected by a driving belt 42 with a pulley 43 mounted adjacent to the right-hand end of the internal grinding wheel spindle 38. A push button switch 44 is provided on the front of the machine base 10 to facilitate starting or stopping the internal grinding wheel driving motor 40.

The external grinding wheel slide 18 is arranged to be adjusted transversely relative to the machine base 10 by means of a rotatable cross feed screw 45 which is engaged by a half nut 46 depending from the wheel slide 18 (Fig. 3). A manually operable feed wheel 47 is provided on the front of the machine base 10 to facilitate a manual transverse adjustment of the wheel slide 18 toward or from the work piece 16 to be externally ground.

A manually operable feed wheel 48 is rotatably supported in a horizontally extending casing 49 which is connected by bevel gears (not shown) with a vertical shaft contained within the vertical housing 50 which is supported on the upper surface of the internal grinding wheel slide 35. The manually operable feed wheel 48 is operatively connected in the conventional manner to move the internal grinding wheel slide 35 transversely relative to the base 10 to adjust the position of the internal grinding wheel 39 relative to the work piece 16 for internal grinding.

Manual table traverse

The table 11 is arranged to be traversed longitudinally relative to the base 10 by means of a manually operable traverse mechanism comprising a manually operable hand wheel 55 which is rotatably supported on a fixed shaft 56 (Fig. 4). A small gear 57 is connected to rotate with the hand wheel 55 and meshes with a gear 58 which is keyed to a shaft 59 which is in turn rotatably journaled in ball bearings mounted in an apron 62 which is fixedly mounted on the front of the machine base 10. A gear 63 is rotatably mounted adjacent to the right-hand end of the shaft 59. The gear 63 meshes with a rack plate 64 depending from the under side of the table 11. The gear 63 is provided with clutch teeth on its left-hand side face (Fig. 4) which are arranged to be engaged by a slidably mounted clutch member 65 which is slidably keyed to the shaft 59. A compression spring 66 normally

maintains the clutch member 65 in engagement with the clutch teeth on the gear 63. To facilitate disengagement of the clutch member 65, a bell crank lever 67 is pivotally supported on a rock shaft 68. The vertical arms of the bell crank lever 67 are provided with studs which engage shoes sliding in a groove in the clutch member 65. An integral horizontally extending arm of the bell crank lever 67 is arranged to be engaged by the head of a screw 69 which is adjustably mounted on the upper end of a piston rod 70. The lower end of the piston rod 70 is formed as a piston 71 which is slidably mounted within a cylinder 72 integral with the apron 62. A compression spring 73 normally tends to hold the piston 71 in a downward position (Fig. 4). When it is desired to disengage the clutch 65, fluid under pressure is admitted in a manner to be hereinafter described through a pipe 74 into a cylinder chamber 75 formed in the lower portion of the cylinder 72. The manually operable traverse mechanism just described serves to facilitate a manual adjustment of the table 11 when it is in an external grinding position, such as that shown in Figs. 1 and 2.

Auxiliary manual table traverse

When the work table 11 is moved toward the right into an internal grinding position, it is desirable to provide an auxiliary table traversing mechanism adjacent to the controls for the internal grinding wheel 39. An auxiliary manually operable feeding mechanism is provided comprising a manually operable hand wheel 80 (Figs. 1 and 2). The auxiliary manually operable table traversing mechanism is identical with the manual traverse mechanism just described and illustrated in Fig. 4; consequently this auxiliary mechanism has not been illustrated in detail. A fluid pressure mechanism is provided for disengaging the clutch in the auxiliary table traversing mechanism comprising a cylinder 81 which is integrally contained within an apron 82 which is fixedly mounted on the front of the machine base 10. A slidably mounted piston 83 is contained within the cylinder 81. A compression spring 88 normally tends to hold the piston 83 in a downward position to engage the clutch teeth. The piston 83 is provided with an upwardly extending piston rod 84 which is provided with an adjustably mounted screw 85 which engages a bell crank lever (not shown) for actuating the clutch to disengage the auxiliary traversing mechanism contained within the apron 82. When it is desired to render inoperative the auxiliary traversing mechanism, fluid under pressure is admitted through a pipe 86 in a manner to be hereinafter described into a cylinder chamber 87 to cause an upward movement of the piston 83 which serves to disengage the clutch (not shown) which is identical with that shown in Fig. 4, to render the auxiliary manually operable traverse wheel 80 inoperative.

Work table control

The table 11 is preferably reciprocated by a hydraulically operated mechanism comprising a cylinder 90 which is supported in fixed relation with the under side of the table 11. A pair of spaced pistons 91 and 92 are slidably mounted within the cylinder 90 and are connected by hollow piston rods 93 and 94, respectively. The hollow piston rods 93 and 94 are connected to hollow brackets 95 and 96, respectively, which are

mounted in fixed relation with the opposite ends of the base 10.

Fluid under pressure is supplied from a suitable source, such as a reservoir 97 formed in a box-like portion of the base 10. A motor driven fluid pump 98 is controlled by a push button switch 99 on the front of the machine base 10. The pump 98 draws fluid through a pipe 100 from the reservoir 97 and forces fluid under pressure through a pipe 101 to a table reversing valve 102. An adjustable relief valve 103 is connected in the pipe line 101 to allow excess fluid under pressure to exhaust directly into the reservoir 97.

The control valve 102 is preferably a two-part valve, one part of which slides relative to the other. A slidably mounted valve stem 104 is provided with a pair of spaced valve pistons 105 and 106. A reduced cylindrical portion 107 of the valve stem 104 passes through a central aperture formed in a slidably mounted reversing valve member 108. The reversing valve member 108 is provided with a plurality of spaced, integrally formed valve pistons 109, 110 and 111. In the position of the valve parts as shown in Fig. 3, fluid under pressure passing through the pipe 101 enters a passage 112 in the valve casing and passes through the ports 113 into a valve chamber 114 and outwardly through a pipe 115, a pipe 116, through the hollow bracket 96, through the hollow piston rod 94 and the hollow piston 92, into a cylinder chamber 117 formed at the right-hand end of the cylinder 90 to cause a movement of the table 11 toward the right.

During this movement fluid within a cylinder chamber 118 formed at the left-hand end of the cylinder 90 exhausts outwardly through the hollow piston rod 93, through the hollow bracket 95, through a pipe 119 and a passage 120, into a valve chamber 121 formed between the valve pistons 109 and 110. Fluid exhausting into the valve chamber 121 passes outwardly through an exhaust pipe 122 which in the normal table operating position passes fluid through an exhaust pipe 123 into the reservoir 97.

A reversing lever 124 is mounted on the forward end of a rock shaft 125. The rock shaft 125 supports a downwardly extending lever 126 the lower end of which is operatively connected to the valve stem 104. The reversing lever 124 may be shifted either manually or by table actuated dogs (not shown) to change the direction of movement of the table 11.

A combined start and stop and speed control valve 127 is provided which is preferably formed integral with the control valve 102, but for the sake of simplicity of illustration, it has been illustrated diagrammatically in Fig. 3 as a separate valve. The valve 127 is preferably located in the exhaust side of the system so as to maintain a uniform pressure on the operating side of the main cylinder 90 during the entire reciprocatory stroke of the cylinder 90 relative to the pistons 91 and 92. The valve 127 comprises a valve stem 128 having formed integrally therewith a plurality of valve pistons 129, 130 and 131. The control valve 127 is arranged so that it may be shifted longitudinally and also rotarily adjusted by means of a control knob 132. The right-hand end face of the valve piston 131 is formed as an angular plane face 133. By rotarily adjusting the valve stem 128, the position of the angular plane end face 133 may be adjusted to open or close a V-port 134 to the desired and predetermined extent when the valve stem is in a table operating position, that is, moved toward the

left (Fig. 3). This rotary adjustment of the valve stem 128 serves as a fine adjustment to cut off more or less of the V-port 134, thereby controlling the exhausting fluid from the table cylinder 90 precisely to regulate the reciprocatory movement of the table 11.

In order that the valve piston 131 may be maintained in the desired adjusted position during the starting and stopping of the table 11, a serrated portion 135 is formed integral with the valve stem 128. An arrow-pointed spring-pressed plunger 136 is supported by the casing of the valve 127 and is maintained in engagement with the serrated portion 135 so that the valve stem 128 may be moved endwise to start and stop the table movement without changing the speed adjustment thereof.

A manually operable stop and start lever 137 is pivotally mounted on a stud 138. The stud 138 is supported by a boss 139 which is formed as an integral projection of an apron 140 which is in turn fixedly mounted to the front of the machine base 10. The control lever 137 is provided with a clearance aperture 141 which surrounds a sleeve 142. The sleeve 142 is supported on the valve stem 128 and is provided with a pair of diagrammatically opposed parallel grooves 143 which are engaged by a pair of diagrammatically opposed studs 144 carried by the control lever 137. It will be readily apparent from the foregoing disclosure that when the control lever 137 is positioned as indicated in Fig. 3, the V-port 134 is closed, thus preventing exhaust of fluid from the table cylinder 90 and maintaining the table 11 in a stopped position.

When it is desired to start the reciprocating movement of the table 11, the control lever 137 is shifted in a counter-clockwise direction (Fig. 3) which movement shifts the valve stem 128 together with the valve pistons 129, 130 and 131 toward the left so that the V-port 134 is opened to allow an exhaust of fluid from the table cylinder 90.

Upon the shifting of the valve stem 128 to the left, the valve piston 130 cuts off the exhaust from the cylinder chamber 75 and a valve chamber 147 connects the pipe 74 with a pipe 148 which is connected to the fluid pressure pipe 101, thereby admitting fluid under pressure through the pipe 74 into the cylinder chamber 75 in the cylinder 72. This raises the piston 71 so that the screw 69 in the valve stem 70 engages the lower arm of the forked bell crank lever 67 to disengage the teeth on the clutch member 65 from the clutch teeth on the gear 63. This makes the manually operable traverse mechanism operated by the hand wheel 55 neutral or inoperative during the hydraulic actuation of the table 11. When the table 11 is stopped by shifting the valve stem 128 toward the right (Fig. 3), the released tension of the springs 73 and 66 will move the piston 71 downwardly, exhausting fluid in the cylinder chamber 75 through the pipe 74. The released tension of the spring 66 will move the clutch member 65 to engage the clutch teeth on the gear 63 so that the hand wheel 55 may be used to traverse the table 11 manually.

When the throttle valve 127 is in a closed position (Fig. 3), it is desirable to provide a suitable by-pass whereby fluid may readily pass from the cylinder chamber 117 into the cylinder chamber 118 and vice versa to facilitate a manual traversing movement of the table 11. A pipe 145 is connected between the valve 102 and the valve

127. Similarly, a pipe 146 is connected between the valve 102 and the valve 127. In the position of the valve 127, the pipes 145 and 146 are connected by the valve chamber 147 formed between the valve pistons 130 and 131. It will be readily apparent from the foregoing disclosure that fluid may readily pass from the cylinder chamber 117 through the pipe 116, the pipe 146, through the valve chamber 147, through the pipe 145 and the pipe 119, into the cylinder chamber 118 so that the table 11 may be readily traversed longitudinally by a manually operable traversing mechanism to be hereinafter described without meeting any resistance from the fluid within the system.

Wheel feeding mechanism

The cross feed screw 45 previously described is slidably keyed within a hollow portion of a rotatable shaft 150. The shaft 150 is journaled at one end in a bearing 151 in a wheel slide base 152 which serves as a support for the forward end of the feed screw 45. The rear end of the feed screw 45 is journaled in a bearing contained within a slidably mounted sleeve 153 which is slidably supported within a cylindrical aperture in the wheel slide base 152 which is fastened to the base 10. It will be readily apparent from the foregoing disclosure that a rotary motion of the manually operated feed wheel 47 may be imparted to rotate the feed screw 45 to transmit a feeding movement through the half nut 46 to the wheel slide 18 and the grinding wheel 17.

In order to facilitate a rapid movement of the external grinding wheel slide 18 to and from an operative position, a hydraulically operated mechanism is provided for moving the feed screw 45 in an axial direction. This mechanism may comprise a hydraulic cylinder 154 which is arranged in axial alignment with the feed screw 45. A slidably mounted piston 155 is contained within the cylinder 154. A double end piston rod 156 is fixedly connected to the piston 155 and is connected at its left-hand end (Fig. 3) to the slidably mounted sleeve 153. It will be readily apparent from the foregoing disclosure that when fluid under pressure is admitted to a cylinder chamber 157 to cause the piston 155 to move toward the left, it will impart a forward approaching or feeding movement through the feed screw 45 to move the external grinding wheel slide 18 and grinding wheel 17. Similarly, as fluid under pressure is admitted to a cylinder chamber 158 to cause the piston 155 to move toward the right into the position illustrated in Fig. 3, a rearward movement of the grinding wheel 17 may be obtained.

A reversing or feed control valve 160 is provided for controlling the admission to and exhaust of fluid from the feed cylinder 154. The valve 160 is a piston type valve comprising a valve stem 161 having formed integrally therewith valve pistons 162, 163, 164 and 165. A compression spring 166 normally serves to hold the valve stem 161 in its right-hand end position (Fig. 3). An electric push type solenoid 167 is operatively connected to the valve stem 161 so that when energized, the solenoid 167 will move the valve stem 161 toward the left against the compression of the spring 166 to reverse the flow of fluid under pressure to the cylinder 154.

Fluid under pressure from the pump 93 passing through the pipe 101 passes through a pipe 168, into a valve chamber located between the valve pistons 163 and 164, and through a pas-

sage 169 into the cylinder chamber 158 to move the piston 155 rearwardly, that is, toward the right (Fig. 3) into the position illustrated. During this movement, fluid within the cylinder chamber 157 exhausts through a passage 170, into a valve chamber located between the valve pistons 162 and 163, and passes outwardly through an exhaust pipe 171 into the reservoir 97. A throttle valve 172 is provided in the exhaust pipe line 171 whereby the rate of exhaust of fluid from the feed cylinder 154 may be regulated as desired so as to control the transverse feeding movement of the grinding wheel 17. The mechanism above described produces a comparatively rapid or reduced forward feeding movement of the grinding wheel 17.

Dash pot feeding mechanism

A suitable fluid pressure control or feed regulating mechanism is provided for modifying the rapid approaching movement caused by the piston 155 to obtain a controlled and predetermined grinding feed of the grinding wheel 17. A self-contained dash pot feed regulator is provided comprising a pair of dash pot cylinders 175 and 176 which contain slidably mounted dash pot pistons 177 and 178. The dash pot pistons and cylinders are arranged with their axes parallel to each other and are spaced on diagrammatically opposite sides of the axis of the piston rod 156. The dash pot pistons 177 and 178 are normally held in a rearward or right-hand position by means of the compression springs. An adjustable stop screw 179 serves to limit the rearward movement of the dash pot pistons 177 and 178. A slidably mounted sleeve 180 surrounds and is supported on the rearwardly extending portion of the piston rod 156. The sleeve 180 is provided with a flanged portion 181 which is either formed integral with or fixedly secured to the sleeve 180. The flange 181 is arranged to engage the right-hand end face of the dash pot pistons 177 and 178, respectively. The stop screw 179 engages the flange 181 and thereby serves to limit the rearward movement of the dash pot pistons 177 and 178.

The rapid approaching or forward feeding movement of the grinding wheel 17 and the wheel slide 18 continues until an adjustable nut 182 on a threaded portion 183 of the rearwardly extending portion of the piston rod 156 engages the right-hand end of the sleeve 180. Continued movement of the piston rod 156 moves the sleeve 180 and the flange 181 toward the left to move both of the pistons 177 and 178 also toward the left. When the flange 181 engages the ends of the dash pot pistons 177 and 178 respectively, the rapid approaching feeding movement of the grinding wheel 17 toward the work piece 16 is reduced to a slower predetermined grinding feed due to the fact that fluid compressed within the dash pot cylinders 175 and 176 respectively which are interconnected exhausts through a passage 184, a needle valve 185, through a pipe 186, into a reservoir 187. By adjusting the aperture of the needle valve 185, a desired and predetermined infeeding movement of the grinding wheel 17 may be obtained.

When fluid is admitted to the cylinder chamber 158 to cause a rearward movement of the piston 155, the sleeve 180 together with the flange 181 is moved rearwardly by means of the released compression of the springs within the dash pot cylinders 175 and 176 which returns the dash pot pistons 177 and 178 respectively to

their rearward position and moves the flange 180 into engagement with the stop screw 179. The rearward movement of the dash pot pistons 177 and 178 serves to draw fluid from the reservoir 187, through a pipe 188 and a ball check valve 189, to fill the dash pot cylinders 175 and 176 for the necessary infeeding movement of the grinding wheel 17. During the infeeding movement of the dash pot pistons 177 and 178, fluid within the dash pot cylinders 175 and 176 serves to hold the ball check valve 189 closed so that fluid within the dash pot cylinders 175 and 176 is forced out through the needle valve 185.

A throttle needle valve 190 is connected by the pipe 183 to a chamber 191 to facilitate exhaust of fluid from the dash pot cylinders 175 and 176 as the passage 184 is closed by the dash pot piston 177. If desired, the throttle valve 190 may be used to produce a very fine, final feeding movement of the grinding wheel 17 just prior to the engagement of a stop surface 193 by an adjustable positive stop 192 which positively limits the forward feeding movement of the grinding wheel 17 toward the work piece 16. In the latter case, two distinct feeds of the grinding wheel 17 may be obtained; manipulation of the needle valve 185 combined with the opening of the needle valve 190 is continued until the passage 184 is cut off, after which the needle valve 190 controls the rate of advance of the grinding wheel 17.

Electrical control

An electrical control circuit is provided for stopping and starting the grinding cycle, comprising a pivotally mounted control lever 200 which is pivotally supported on a bracket in a fixed relationship with the front of the machine base 10. The control lever 200 is arranged when moved in a counterclockwise direction (Fig. 3) to actuate a push button starter switch 201 or when rocked in a clockwise direction to actuate a push button stop switch 202 whereby the grinding cycle may be started or interrupted when desired. Each push button switch 201 and 202 is connected through a magnetic starter or relay switch 203 to control the energizing and deenergizing of the push type solenoid 167 so as to actuate the feed control valve 160 as desired. A normally closed limit switch 204 is mounted on the headstock 15 and is arranged to be actuated by a cam plate 205 which is fixedly mounted relative to the base 10 (Fig. 4). When the table 11 is traversed toward the right into an internal grinding position, an actuating roller 206 of the limit switch 204 rides onto the cam plate 205 which opens the contacts of the limit switch 204 and thus opens a circuit to deenergize or to prevent energization of the solenoid 167 so as to prevent an infeeding movement of the external grinding wheel 17 and the wheel slide 18 while the table 11 is in an internal grinding position. This prevents the grinding wheel 17 from being fed accidentally into the rear side of the headstock 15.

A control valve 208 is provided for controlling the passage of fluid under pressure to the cylinders 72 and 81, respectively, to render the manually operable traverse wheels 55 and 80 together with their respective mechanisms inoperative in a manner to be hereinafter described. The control valve 208 is a piston type valve comprising a valve stem 209 having formed integrally therewith valve pistons 210, 211, 212

and 213. The valve stem 209 is normally held in the position illustrated in Fig. 3 by means of a compression spring 214. An electric pull type solenoid 215 is operatively connected so that when energized it will shift the valve stem 209 toward the left (Fig. 3) to change the direction of flow of fluid under pressure. In the position illustrated in Fig. 3, fluid under pressure from the pump 98 passing through the pipe 101 passes through a pipe 216 into a valve chamber located between the valve pistons 211 and 212 and passes outwardly through the pipe 86 into the cylinder chamber 87 of the cylinder 81 to move the valve piston 83 upwardly, and thus to disconnect the clutch on the auxiliary table traverse mechanism so as to render the hand traverse wheel 80 inoperative.

In the above position of the valve 208, fluid within the cylinder chamber 75 formed in the cylinder 72 may exhaust through the pipe 74, through a valve chamber 217 formed between the valve pistons 129 and 130 in the control valve 127, and pass outwardly through a pipe 219 into a valve chamber located between the valve pistons 210 and 211 of the valve 208. Fluid exhausting through the valve chamber located between the valve pistons 210 and 211 exhausts through a pipe 220 into the reservoir 97.

When the solenoid 215 is energized to shift the valve stem 209 into a left-hand end position, fluid under pressure passing from the pipe 216 into a valve chamber located between the valve pistons 211 and 212 may pass outwardly through the pipe 219, through the valve chamber 217 in the control valve 127, into the cylinder chamber 75 to move the piston 71 upwardly so as to move the clutch member 65 out of engagement with the clutch teeth formed on the gear 63, thus rendering inoperative the manually operable table traverse mechanism contained in the apron 62 which traverses the table 11 during an external grinding operation.

A push type solenoid 225 is operatively connected by a link 226 with a stud 227 which is supported at the lower end of the control lever 137. Assuming the control lever 137 is to be rocked in a counterclockwise direction from the position illustrated in Fig. 3 during the hydraulic traversing movement of the table 11, when the solenoid 225 is energized the link 226 will be moved toward the left to rock the control lever 137 in a clockwise direction to close the V-port 134 and thus stop the hydraulic movement of the table 11.

It is desirable automatically to control the energization of the solenoids 215 and 225 in timed relation with the movement of the table 11 to an internal grinding position. A snap action, single pole, double-throw switch 228 is mounted on the base 10 of the machine. An actuating lever 229 of the switch 228 is arranged in the path of a longitudinally adjustable table dog 230 which is supported by the T-slot 231 formed in the front edge of the table 11. The dog 230 is arranged so that when the table 11 is moved toward the right into an internal grinding position, the dog 230 engages the actuating lever 229 of the switch 228 and rocks it from the dotted line position (Fig. 3) to the dot-dash position 229a and snaps the electrical contact prongs in a closed position which serves to energize the solenoids 215 and 225. The energization of the solenoid 215 serves to shift the valve stem 209 toward the left so that fluid contained within the cylinder chamber

87 may exhaust through the pipe 86 into a valve chamber located between the valve pistons 212 and 213 and pass outwardly through the exhaust pipe 220 into the reservoir 91, thus allowing the piston 83 to move downwardly under the released compression of the spring 88 which surrounds the piston rod 84. This movement of the piston 83 serves to render operative the auxiliary manually operable table traverse mechanism as controlled by the hand wheel 80 so that the table 11 may be traversed longitudinally during the internal grinding operation from a point adjacent to the operator's station during this operation.

At the same time as the solenoid 215 is energized, the solenoid 225 is also energized to shift the control lever 131 into the position illustrated in Fig. 3, thus closing the V-port 134 to stop the hydraulic traverse of the table 11 and at the same time allowing fluid under pressure from the valve 208 to pass through the pipe 219 through the valve chamber 217 and in the valve 127, into the cylinder chamber 75, to cause an upward movement of the piston 71, thus shifting the clutch member 65 toward the left (Fig. 4) into a disengaged position, thus rendering the normal table traversing mechanism as governed by the manually operable hand wheel 55 inoperative during the internal grinding operation.

After the internal grinding operation, the table 11 is again shifted toward the left into position for an external grinding operation. The initial movement of the table 11 toward the left is manually controlled until the lever 229 is rocked by the dog 230 and snaps the switch 228 to the open position. Then the table 11 may be shifted hydraulically to the desired loading position.

Operation

The operation of the improved external and internal cylindrical grinding machine will be readily apparent from the foregoing disclosure. A work piece 16 to be ground is mounted on the face plate on the headstock spindle 26, after which the work table 11 is moved longitudinally to position the external grinding wheel 17 in operative relation with the external portion of the work piece 16 to be ground. The control lever 137 is shifted to open the V-port 134 to cause the desired longitudinal movement of the work table 11.

By manipulation of the lever 124, the direction of movement of the table 11 may be readily controlled. When the work table 11 has been moved to the predetermined external grinding position, the control lever 200 may be shifted in a counterclockwise direction (Fig. 3) to energize the solenoid 167 in a manner above described to shift the valve stem 161 so as to admit fluid under pressure to the cylinder chamber 157 to initiate a forward feeding movement of the external grinding wheel 17 and its supporting wheel slide 18. The forward feeding movement of the grinding wheel 17 is continued until the contact collar of the positive stop 192 engages the positive stop surface 193 after which the control lever 200 may be rocked in a clockwise direction to actuate the push button switch 202 to break the circuit, thus deenergizing the solenoid 167 which allows the released compression of the spring 166 to return the valve stem 161 into the position illustrated in Fig. 3 so that fluid under pressure is admitted to the cylinder chamber 158 to cause a rearward movement of the external grinding wheel 17 to an inoperative position.

When it is desired to move the table 11 into an internal grinding position, the control lever 137 is moved in a counterclockwise direction (Fig. 3) to shift the valve stem 128 toward the left to open the V-port 134 so as to allow fluid to exhaust from the table cylinder 90, thus starting a hydraulic traversing movement of the table 11. The table 11 moves toward the right into an internal grinding position until the table dog 230 engages and actuates the snap switch 228 to close a circuit, thus energizing the solenoids 215 and 225 to shift the valve stem 209 toward the left (Fig. 3) and to move the start and stop valve 127 into the position illustrated in Fig. 3. This movement allows the piston 83 to move downwardly so as to render operative the auxiliary manual traverse mechanism as governed by the hand wheel 80 so that the table 11 may be traversed manually during an internal grinding operation. During the internal grinding operation, the internal grinding wheel 39 together with its supporting slide 35 may be moved transversely by means of the manually operable feed wheel 48.

When the table 11 is moved toward the right into the internal grinding position, the cam plate 205 which is fixed relative to the base 10 engages the roller 206 to actuate and open the limit switch 204 so as to open the circuit and prevent energization of the solenoid 167, thus preventing an infeeding movement of the external grinding wheel 17 during the time when the table 11 is moved toward and into an internal grinding position. It will thus be seen that an interlock has been provided to render the infeeding movement of the external grinding wheel 17 inoperative when the table 11 is in an internal grinding position. An interlock is provided also to render the auxiliary table traverse wheel 80 inoperative when the table 11 is in an external grinding position. An interlock is also provided to render the auxiliary traverse wheel 80 operative and the manually operable traverse wheel 55 inoperative while the work table 11 is in an internal grinding position.

The manually operable hand traverse mechanisms for traversing the work table 11 when in an external and an internal grinding position, respectively, are preferably two-speed hand traverse mechanisms, such as that disclosed in the expired U. S. patent to C. H. Norton, et al. No. 1,299,765 dated April 8, 1919, to which reference may be had for details of disclosure not contained herein. Control knobs 235 and 236 are provided on the hand wheels 55 and 80, respectively, for shifting the speeds of the traverse mechanisms.

In grinding relatively short work pieces, the headstock 15 is positioned as indicated in Figs. 1 and 2 for an external operation, after which the headstock 15 is shifted longitudinally on the table 11 into engagement with a stop 234 for an internal grinding operation. While the headstock is thus positioned, the table 11 is moved toward the right into an internal grinding position.

It will thus be seen that there has been provided by this invention apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying

drawings is to be interpreted as illustrative and not in a limiting sense.

I claim:

1. In a grinding machine having a base, a longitudinally movable work table thereon, a rotatable work support on said table, a rotatable grinding wheel, a transversely movable slide therefor, a second rotatable grinding wheel, a transversely movable slide therefor which is spaced from said first slide, means to move said first grinding wheel slide transversely, means including a solenoid operatively connected to initiate an infeeding movement of the first grinding wheel, means to traverse said table to a second grinding position, and an interlock including an electric switch which is automatically actuated by movement of the table to control an electric circuit and prevent actuation of the solenoid to initiate an infeeding movement of the first grinding wheel while the table is in a second grinding position.

2. In a grinding machine having a base, a longitudinally movable work table thereon, a rotatable work support on said table, an external rotatable grinding wheel, a transversely movable slide therefor, an internal rotatable grinding wheel, a transversely movable slide therefor which is spaced from said first slide, means to move said external grinding wheel slide transversely, means including a solenoid operatively connected to initiate an infeeding movement of the external grinding wheel, manually operable means to traverse said table to an internal grinding position, and an interlock including an electric switch which is automatically actuated by movement of the table to control an electric circuit and prevent actuation of the solenoid to initiate an infeeding movement of the external grinding wheel while the table is in an internal grinding position.

3. In a grinding machine having a base, a longitudinally movable work table thereon, a rotatable work support on said table, an external rotatable grinding wheel, a transversely movable slide therefor, an internal rotatable grinding wheel, a transversely movable slide therefor which is spaced from said first slide, a hydraulic piston and cylinder to move said external grinding wheel slide transversely, a control valve therefor, means normally to maintain said valve in a position to move and maintain said slide in a rearward or inoperative position, a solenoid operatively connected to shift said valve to initiate an infeeding movement of the external grinding wheel, manually operable means to traverse said table to an internal grinding position, and an interlock including a normally closed switch which is automatically opened by movement of the table to break a circuit and prevent energization of the solenoid while the table is in an internal grinding position.

4. In a grinding machine having a longitudinally movable work table, a transversely movable rotatable grinding wheel, a manually operable traverse mechanism for traversing said table when in a first grinding position, means including a clutch to render said mechanism operative or inoperative, a second manually operable traverse mechanism which is spaced from the first for traversing said table when in a second grinding position, means including a clutch to render said second traverse mechanism operative or inoperative, and means including an interlock whereby one of said clutches may be engaged while the other is held disengaged.

5. In a grinding machine having a longitudi-

nally movable work table, a transversely movable rotatable grinding wheel, a manually operable traverse mechanism for traversing said table when in a first grinding position, means including a clutch to render said mechanism operative or inoperative, means including a fluid pressure piston and cylinder to disengage said clutch, a second manually operable traverse mechanism which is spaced from the first for traversing said table when in a second grinding position, means including a clutch to render said second mechanism operative or inoperative, a fluid pressure piston and cylinder to disengage said clutch, and a control valve to control the admission of fluid under pressure to one or the other of said cylinders.

6. In a grinding machine having a longitudinally movable work table, a transversely movable rotatable grinding wheel, a second transversely movable rotatable grinding wheel spaced from said first wheel, a manually operable traverse mechanism for traversing said table when in an operative position with relation to the first wheel, means including a clutch to render said mechanism operative or inoperative, means including a fluid pressure piston and cylinder to engage said clutch, a second manually operable traverse mechanism which is spaced from the first for traversing said table when in an operative position relative to said second grinding wheel, means including a clutch to render said second mechanism operative or inoperative, a fluid pressure piston and cylinder to disengage said clutch, and a control valve to control the admission of fluid under pressure to either one or the other of said cylinders.

7. In a grinding machine having a longitudinally movable work table, a transversely movable rotatable external grinding wheel, a transversely movable rotatable internal grinding wheel spaced from said first wheel, a manually operable traversing mechanism for traversing said table when in an external grinding position, means including a clutch to render said mechanism operative or inoperative, means including a fluid pressure piston and cylinder to disengage said clutch, a manually operable traverse mechanism for traversing said table when in an internal grinding position, a clutch which is normally engaged to control said mechanism, a fluid pressure piston and cylinder to disengage said clutch, and a control valve to control the admission of fluid under pressure to either one or the other of said cylinders.

8. In a grinding machine having a longitudinally reciprocable table, a piston and cylinder to reciprocate said table, a reversing valve, a control valve operatively connected therewith, a pair of spaced hand traverse mechanisms whereby the table may be manually traversed from two spaced operating stations, a clutch in each of said mechanisms, a spring normally to maintain said clutches in engagement, a separate hydraulic piston and cylinder to disengage each of said clutches, and a solenoid actuated valve to admit fluid under pressure to one or the other of said clutch cylinders.

9. In a grinding machine having a longitudinally reciprocable table, a piston and cylinder to reciprocate said table, a reversing valve, a control valve operatively connected therewith, a pair of spaced hand traverse mechanisms, a normally engaged clutch in each of said mechanisms, a separate hydraulic piston and cylinder to disengage each of said clutches, a solenoid actuated

valve to admit fluid under pressure to one or the other of said clutches, and fluid connections whereby both of said clutches are disengaged and both of the hand traverse mechanisms rendered inoperative during the hydraulic movement of said table.

10. In a grinding machine having a longitudinally reciprocable table, a piston and cylinder to reciprocate said table, a reversing valve, a control valve operatively connected therewith, a pair of spaced hand traverse mechanisms for manually traversing said table, one of said mechanisms serving to traverse the table when in an external grinding position and the other of said mechanisms serving to traverse said table when in an internal grinding position, a clutch in each of said mechanisms, a hydraulic piston and cylinder to disengage each of said clutches, and a solenoid actuated valve to admit fluid under pressure to one or the other of said cylinders, said solenoid valve normally being in a position to admit fluid under pressure to the clutch cylinder to render the internal manual traverse mechanism inoperative.

11. In a grinding machine having a longitudinally movable work table, a piston and cylinder to reciprocate said table, a reversing valve, a control valve operatively connected therewith, a pair of spaced hand traverse mechanisms for manually traversing said table from two spaced posi-

tions, separate hydraulic piston and cylinders to disengage each of said clutches, a solenoid actuated valve to admit fluid to one or the other of said clutch cylinders, and fluid connections between the control valve whereby fluid pressure is passed through a chamber in said control valve into the clutch cylinder to render the manually operable table traverse mechanism inoperative when the control valve is opened to start 10 hydraulic traverse of the table.

12. In a grinding machine having a longitudinally reciprocable table, a piston and cylinder to reciprocate said table, a reversing valve, a control valve operatively connected therewith, a pair 15 of spaced hand traverse mechanisms whereby the table may be manually traversed from two spaced stations, a clutch in each of said mechanisms, a separate hydraulic piston and cylinder to disengage each of said clutches, a solenoid actuated 20 valve to admit fluid under pressure to one or the other of said clutch cylinders, and an electric switch which is closed by movement of said table into an internal grinding position to actuate and shift said solenoid control valve so as to 25 admit fluid under pressure to render the manually operable traverse mechanism inoperative while the internal manually operable traverse mechanism is rendered operative.
